UNITED STATES PATENT OFFICE.

IRVING WASHINGTON CADWELL, OF DENVER, COLORADO.

LAUNDRY-EXTRACTOR.

1,191,661.

Specification of Letters Patent. Patented July 18, 1916.

Application filed December 28, 1915. Serial No. 69,033.

To all whom it may concern:

Be it known that I, IRVING W. CADWELL, a citizen of the United States, and a resident of Denver, in the county of Denver and State of Colorado, have invented certain new and useful Improvements in Laundry-Extractors, of which the following is a specification.

My invention relates to the extraction of water from articles being laundered, and the main object thereof is to provide means for accomplishing this result in an easier and simplified manner than by the present method, whereby much time, labor, and money will be saved and whereby the extraction will be performed in a more satisfactory manner than at present.

My invention is fully described in the following specification, of which the accompanying drawings form a part, in which like characters refer to like parts in each of the views, and in which:—

Figure 1 is a vertical section taken through one form of embodiment of my invention, as on the line 1—1 of Fig. 2; Fig. 2 is a section taken on the line 2—2 of Fig. 1; and Fig. 3 is a section taken on the line 3—3 of Fig. 1.

In the drawings forming a part of this application I have shown a floor or platform 4, within a laundry, above and beneath which is a frame 5 shown as of T-bars carrying a platform 6 beneath the floor 4 and cross-heads 7 and 8 at its top above said floor. Arranged on the platform 6 is a jack 9, of pneumatic type, provided with a piston 10, a hollow rod 11 thereon projecting through and slightly above the floor 4 when the piston is in lowermost position, and with a supply pipe 12, any suitable equivalent of which jack might be provided. Vertically slideable in the cross-heads 7 and 8 is a rod 13 screw-threaded for a portion of its length to engage an internally threaded hand-wheel 14 confined between said cross-heads and whereby said rod may be vertically adjusted. The rod 13 carries a presser-plate 15 at its lower end and a cross-head 16 at its upper end the arms of which, four in number, are secured to verti-

cal rods 17 slideable in guides 18 on the frame 5.

At 19 I have shown a truck provided with wheels 20, a tank 21, a drain 22 therefor, and a perforated basket 23 within said tank and separated from the walls thereof, braces 24 being shown at the corners and which braces are provided with perforations 25 slightly greater in diameter than the diameter of the rods 17 and so arranged as to receive said rods 17 in a manner and for a purpose later explained.

The truck 19 is rolled to a washing machine and the articles just washed in the latter are deposited within the basket 23, after which the truck is rolled within the frame 5 in such position as to receive the rods 17 when the hand-wheel 14 is revolved in the proper direction to lower the rod 13, this movement also carrying the presser-plate into the basket 23, the lowering of the rod 13, however, being only so far as to engage the rods 17 with the truck to guide the latter in its vertical movement and to insure a closure of the top of the basket 23. When the parts are in this position, the fluid is admitted to the jack to raise the piston and thus raise the truck from the floor 4 and which truck movement squeezes the water out of the clothes or other articles in the basket, the water passing through the perforations of the basket and through the drain and may be led to any desired point, such as a sewer.

From the foregoing it will be seen that I avoid the present necessity of loading the clothes from the washing machine into a truck and from the truck into the extractor, my truck and extractor basket constituting a unit and, because of the jack 9, the presser plate 15, and the truck guides, the extraction occurs with but one handling of the clothes instead of two as at present.

While I have shown one form of embodiment of the invention, I do not confine myself thereto, as many modifications thereover may suggest themselves and still be within the spirit of the invention and within the scope of the appended claim.

Having fully described my invention,

what I claim as new, and desire to secure by Letters Patent, is:—

As an article of manufacture, for use in a press, a transportable tank, a perforated cylinder within said tank, and braces between said tank and cylinder having perforations adapted to receive guide rods on said press.

In testimony whereof I have signed my name to this specification in the presence of 10 two subscribing witnesses.

IRVING WASHINGTON CADWELL.
